DESIGN FOR A PHONOGRAPH TONE ARM

Emil I. Harman, Philadelphia, Pa., assignor to
Philco Radio and Television Corporation,
Philadelphia, Pa., a corporation of Delaware

Application January 31, 1941, Serial No. 98,622

Term of patent 14 years

To all whom it may concern:

Be it known that I, Emil I. Harman, a citizen
of the United States, residing in Philadelphia,
Philadelphia County, Pennsylvania, have invent-
ed a new, original, and ornamental Design for
Phonograph Tone Arm, of which the following is
a specification, reference being had to the accom-
panying drawings, forming part thereof, in
which:

Fig. 1 is a perspective view of a phonograph
tone arm showing my new design; and

Fig. 2 is a side elevational view of the tone
arm as viewed from the left of Fig. 1.

I claim:

The ornamental design for a phonograph tone
arm, substantially as shown.

EMIL I. HARMAN.
